TOWING DEVICE

Frederick H. Miller, Portland, Oreg.

Application January 6, 1933. Serial No. 650,540

9 Claims. (Cl. 280—33.14)

My invention relates to devices commonly known as tow lines by which one motor vehicle may tow another or be towed by another when for any reason it is desirable to do so.

5 One of the objects of my invention is to provide a tow line that will always be ready for instant use, i. e., be located in such position on the vehicle that it will be unnecessary to lift up seats or open tool boxes to get at the rope. 10 Again, it is an object to provide a towing device wherein the tow line is held contained within a tube or casing that is longitudinally supported beneath the vehicle, preferably on the front and rear axles thereof in such a manner 15 that it will be protected against the elements, such as dirt, water, ice, snow, etc., and thus leave it free for smooth and easy operation when it is necessary or desirable to use it. Again, it is an object of my invention to provide a towing 20 device with a spring retracted line that can be used from either end of the vehicle and a line of as great a length as possible.

When towing a car there is always danger when coming to certain unforeseen stops, such as 25 railroad crossings or traffic stops, that the towed car will run over the tow rope; my invention therefore has for an object to provide a towing device which overcomes this objection by taking up slack all the time as the same occurs and 30 preventing the cable from touching the ground at any time.

Further, it is an object of my invention to provide a towing device in which the slack take-up spring works in both directions so that the tow 35 line can be used to connect with either a towing vehicle in front or a vehicle to be towed in the rear.

Further, it is an object of my invention to provide a towing device in which the slack take-up 40 spring also serves as a shock absorber.

Further, it is an object to provide a towing device in which provision is made to protect the spring against being mashed and tangled by overcompression and functionally to interpose 45 between the tow line and the spring a rigid abutment just prior to the time when the spring reaches its maximum safe compression limit.

Again, it is an object of my invention to provide a towing device of small diameter and of 50 such design and construction that it can be applied to any existing make of car without substantial alterations in the structure thereof.

Other objects of my invention will in part be obvious and in part be pointed out hereinafter. 55 To the attainment of the aforesaid objects

and ends, the invention still further resides in the novel details of construction, combination and arrangement of parts, all of which will be first fully described in the following detailed description, then be particularly pointed out in 80 the appended claims, reference being had to the accompanying drawing in which:

Figure 1 is a diagrammatic view illustrating the invention in use.

Figure 2 is an enlarged longitudinal section of 85 one end of the device, the tow line being in the housed or retracted position.

Figure 3 is a view similar to Figure 2, showing the other end of the device.

Figure 4 is an end elevation of the device 90 shown in Figure 2, with the connecting loop attachment removed.

Figure 5 is an elevation of the connecting loop attachment, the coupling pin being omitted.

In the drawing in which like numerals of 95 reference designate like parts in all of the figures, 1 and 2 represent similar sockets having flanges 3 through which suitable clips 4 may be passed to bolt the sockets to the front or rear axles 26 and 27 of the vehicle 25. Each socket 80 1 and 2 has one end provided with a web having an opening 6 for the passage of the rigid coupling head of the tow line. It also has a slot 7 to pass the stop pin 16 of the head 12.

The protected tube or housing 5 has its ends 85 fitted into the sockets 1 and 2 and extends the length of the vehicle from socket to socket. Some play may be left between the ends of the tube 5 and the heads of the sockets 1 and 2 if desired to allow for any slight variations in the 90 distance between axle and axle which may be due to one cause or another (as, for instance, temperature changes which cause expansion and contraction.)

Fitted within the tube 5 at each end and slidable therein with a relatively close sliding fit are pistons 8, the outer ends of each of which have openings 10 for the passage of the coupling heads 12 of the tow line 14, these heads being socketed at 13 to receive the ends of the tow line 14 to 100 which they are rigidly secured by welding or any other suitable way. The free ends of the coupling heads 12 have tapered noses 15 to assist in their entry into the sockets 19 of the attachment by which the end of the tow line is connected to the towing vehicle or to the vehicle being towed, as the case may be. This attachment consists of a socket 19 having pin holes 20 through which, and through the slots 17 in the coupling heads 12, the coupling pins 18 may be 110

passed. The attachment also includes a short length of rope 22 one end of which is secured to the eye 21 of the socket 19 and the other end is secured to a hook 23 so that the rope 22 may be 5 looped around an axle and the hook 23 caught in the eye 21 (see Figure 1). In order that the coupling pin 18 may not be lost it may be connected by a tie rope 24 to the socket eye 21. The attachment just referred to is small, the length 10 of the rope 22 being less than a foot, and can be carried in a pocket of the vehicle door or any other convenient place so as always to be at hand.

An oil or grease cup 28 may be provided by 15 means of which the tube 5 may be supplied with lubricant if desired.

In the normal position of the parts when the vehicle is not towing or being towed, the stops 16 are passed inwardly through the slot 7 and 20 the head 12, given a quarter turn. (See Figures 2 and 3). When in this position the tension of 25 the spring presses the heads 9 against the pins 16 and in turn presses those pins against the closed ends of the sockets 1 and 2, this holds the tow line against rattling. When it is desired to 30 have the vehicle towed or to tow a vehicle, as the case may be, the particular end of the tow line to be pulled out is given a quarter turn to bring the pin 16 out through the slot 7 and the socket 35 attachment 19 is connected. The connection of the socket may be made first and then the member 12 be given a quarter turn to line up the pin 16 with the slot 7 if desired. Upon pulling out the end of the tow line the spring 11 will be compressed.

The length of the pistons 8 are such that just 40 before the spring reaches its maximum compression these pistons will engage one another and thus form a rigid abutment, the head 9 of the advance piston resting against the end of the socket 1. The pin 16 of the rear head 12 thus 45 imparts its force through the rigid abutment 8-8 and advance socket 1 to the adjacent axle of the vehicle. When the tow line is released the spring 11 will retract it. The tapered nose 15 of the head 12 that is within the pipe 5 during the towing act will easily find its way through the opening in the socket 2 or 1 as the case may be, and pass out again to the neutral position. In 50 the practical embodiment of my invention the tube 5 may be made of tubing having a diameter of $\frac{3}{8}$ " outside and $\frac{3}{4}$ " inside; a $\frac{1}{4}$ " steel wire rope and a No. 10 piano wire spring may be used. A tube of the diameter stated can be pushed 55 through any 1" opening in the running gear and the socket members 1 and 2 may be fitted over the ends of the pipe member with ease.

It will be seen from the foregoing description 60 taken in connection with the accompanying drawing that my towing device will maintain a taut rope while towing; it can be attached to all models of cars without alterations of the same; all moving parts are enclosed when not in use, thus insuring long life of the frail parts; no part 65 of the device is exposed to get caught on road obstructions; the construction of the device is neat and parts are easy to replace and the cost of the complete device is not much more than that of a good tow rope; when attached to a car it becomes a part of the same and is not readily 70 recognizable as a towing device; it insures safety and eliminates worry and danger connected with a car running over the tow rope; due to its light construction it may not absorb shocks under all 75 conditions, the prime object being to keep the

rope taut once the car is under way and to maintain the same taut when the car is brought to a stop, although to the extent of the spring's power it serves also as a shock absorber.

Other objects of my invention will be clear to 80 those skilled in the art to which it relates.

What I claim is:

1. A towing device including a pair of sockets, means securing said sockets beneath a vehicle at the front and back thereof respectively, a protecting tube having its ends located in the respective sockets, a tow line extending the length of said tube and including coupling heads projecting through apertures in the remote ends of said sockets, and spring means within said tube 85 and extending from end to end thereof for holding said tow line taut, said spring means including pistons slideable within the respective ends of said tube, a spring extending from piston to piston within the tube, and abutments on the tow line heads against which said pistons 90 abut.

2. A towing device including a pair of sockets, means securing said sockets beneath a vehicle at the front and back thereof respectively, a protecting tube having its ends located in the respective sockets, a tow line extending the length of said tube and including coupling heads projecting through apertures in the remote ends of said sockets, and spring means within said tube 100 and extending from end to end thereof for holding said tow line taut, said spring means including pistons slideable within the respective ends of said tube, a spring extending from piston to piston within the tube, and abutments on the tow line heads against which said pistons 105 abut, said sockets having provisions to pass said abutments when they are in one position and to prevent passage of said abutments when they are in another position.

3. A towing device including a pair of sockets, 115 means securing said sockets beneath a vehicle at the front and back thereof respectively, a protecting tube having its ends located in the respective sockets, a tow line extending the length of said tube and including coupling heads 120 projecting through apertures in the remote ends of said sockets, and spring means within said tube and extending from end to end thereof for holding said tow line taut, said spring means including pistons slideable within the respective 125 ends of said tube, a spring extending from piston to piston within the tube, and abutments on the tow line heads against which said pistons abut, said abutments comprising radial projections on said heads, said sockets having slots to 130 pass said abutments when they align with the slots only.

4. A towing device including a pair of sockets, means securing said sockets beneath a vehicle at the front and back thereof respectively, a protecting tube having its ends located in the respective sockets, a tow line extending the length of said tube and including coupling heads 135 projecting through apertures in the remote ends of said sockets, spring means within said tube 140 and extending from end to end thereof for holding said tow line taut, and a coupling attachment comprising a socket to receive the outer end of a coupling head, means to hold said socket to said head, a flexible cable having at 145 one end a hook and having its other end connected to said socket for the purposes described.

5. A towing device including a pair of sockets, means securing said sockets beneath a vehicle at the front and back thereof respectively, a pro- 150

5. A towing device including a pair of sockets, means securing said sockets beneath a vehicle at the front and back thereof respectively, a protecting tube having its ends located in the respective sockets, a tow line extending the length of said tube and including coupling heads projecting through apertures in the remote ends of said sockets, and spring means within said tube and extending from end to end thereof for holding said tow line taut, said spring means including pistons slideable within the respective ends of said tube, a spring extending from piston to piston within the tube, and abutments on the tow line heads against which said pistons abut, and a coupling attachment comprising a socket to receive the outer end of a coupling head, means to hold said socket to said head, a flexible cable having at one end a hook and having its other end connected to said socket for the purposes described.

6. A towing device including a pair of sockets, means securing said sockets beneath a vehicle at the front and back thereof respectively, a protecting tube having its ends located in the respective sockets, a tow line extending the length of said tube and including coupling heads projecting through apertures in the remote ends of said sockets, and spring means within said tube and extending from end to end thereof for holding said tow line taut, said spring means including pistons slideable within the respective ends of said tube, a spring extending from piston to piston within the tube, and abutments on the tow line heads against which said pistons abut, said sockets having provisions to pass said abutments when they are in one position and to prevent passage of said abutments when they are in another position, and a coupling attachment comprising a socket to receive the outer end of a coupling head, means to hold said socket to said head, a flexible cable having at one end a hook and having its other end connected to said socket for the purposes described.

7. A towing device including a pair of sockets, means securing said sockets beneath a vehicle at the front and back thereof respectively, a protecting tube having its ends located in the respective sockets, a tow line extending the length of said tube and including coupling heads projecting through apertures in the remote ends of said sockets, and spring means within said tube and extending from end to end thereof for holding said tow line taut, said spring means including pistons slideable within the respective

ends of said tube, a spring extending from piston to piston within the tube, and abutments on the tow line heads against which said pistons abut, said abutments comprising radial projections on said heads, said sockets having slots to pass said abutments when they align with the slots only, and a coupling attachment comprising a socket to receive the outer end of a coupling head, means to hold said socket to said head, a flexible cable having at one end a hook and having its other end connected to said socket for the purposes described.

8. In combination with the front and rear axles of a vehicle, a towing device comprising a pair of sockets, means to secure said sockets to the front and rear axles of the vehicle, a tube having its ends held in said sockets respectively, said sockets each having a wall at its outer end provided with an aperture, a tow line normally located within said tube and having heads at its ends one of which projects into the aperture of one socket wall and the other projects through the aperture of the other socket wall, cuppistons located one at either end of said tube and having opposed open ends, a coil spring having its ends in said pistons and extending from one piston to the other within the tube, lugs extending laterally from the heads of the tow line to lie between the outer ends of the pistons and the adjacent sockets respectively, the sockets having slots to pass said abutments only when the abutments are in alignment with the slots.

9. A towing device including a pair of sockets, means securing said sockets beneath a vehicle at the front and back thereof respectively, a protecting tube having its ends located in the respective sockets, a tow line extending the length of said tube and including coupling heads projecting through apertures in the remote ends of said sockets, and spring means within said tube and extending from end to end thereof for holding said tow line taut, said spring means including pistons slideable within the respective ends of said tube, a spring extending from piston to piston within the tube, and abutments on the tow line heads against which said pistons abut, said pistons being hollow and of a combined length greater than that of the spring when fully compressed.
